SUSPENSION CLAMP

Application filed November 19, 1927. Serial No. 234,374.

My invention relates to conductor clamps and particularly to suspension clamps for supporting high-voltage transmission-line conductors.

5 One object of my invention is to provide a clamp, of the above-indicated character, that shall materially reduce the mechanical stresses resulting therein and in the adjacent insulator and tower parts, from oscillations 10 of the conductor supported thereby.

Another object of my invention is to provide a clamp that shall embody substantially universally, relatively movable clamping and supporting elements.

15 Another object of my invention is to provide a conductor clamp that shall so embody a spring clamping element and a ball for holding the spring in clamping condition as to reduce friction between the spring and 20 ball and to permit them to have desirable and effective relative movement without reducing the clamping forces exerted by the spring.

Another object of my invention is to provide a conductor clamp in which parts shall 25 so universally move about a point on the axis of the conductor, as it would normally extend in similar clamps, as to compensate for vibrations in substantially all directions of movement of the conductor.

30 Another object of my invention is to provide a clamp embodying parts, normally adapted to be positively held in clamping relation and to assume relatively loose released relation, that shall be so inter-linked as to 35 permit free relative movement of the parts in the clamped condition thereof and to prevent separation of the parts in the released condition thereof.

40 A further object of my invention is to provide a clamp that shall be simple and durable in construction, economical to manufacture and effective in its operation.

Heretofore, in high-voltage transmission-line practice, it has been usual to employ 45 clamps, such as those embodying U-bolts, J-bolts and the like, for rigidly and permanently holding the conductors in place.

It has also been recently suggested to employ clamps known as slip clamps, whereby, 50 in response to predetermined line conditions,

such as breaking of the conductors, the conductors are permitted to slip through the clamps to prevent undue stresses in the clamps, insulators and tower parts.

A clamp of still different type has been suggested in which a limited universal relative movement is permitted between the clamping members and a suspension element therefor.

However, in the latter clamp, the point about which the parts universally move is laterally offset from the conductor axis and the clamp is not adapted to automatically release the conductor under any conditions likely to occur in service.

It is my aim to provide a transmission-line clamp that shall embody certain features of the clamps heretofore employed, but that shall also embody features which shall render it an improvement thereover, particularly with reference to the above-mentioned clamp 70 in which a certain universal movement is permitted.

Accordingly, in practicing my invention, I provide a supporting or suspension element and cooperating clamping members that are so constructed and related as to permit the clamping members to have substantially universal movement relative to the suspension element. This movement is centered about a point on an axis that would normally be the axis of the conductor in an ordinary clamp having a straight conductor-receiving channel, whereby both oscillations along a conductor and turning or torsional vibrations are prevented from transmitting 85 damaging stresses to the supporting element and adjacent supporting parts.

Figure 1 of the accompanying drawings is a side view, partially in elevation and partially in section, of a clamp constructed in accordance with my invention;

Fig. 2 is a view, partially in elevation and partially in section, taken along the line II-II of Fig. 1;

Fig. 3 is a view, similar to Fig. 1, of a modified form of my invention; and

Fig. 4 is a view, similar to Fig. 2, of the structure shown in Fig. 3.

Referring to Figs. 1 and 2, the clamp comprises, in general, a lower conductor-re-

ceiving or clamping member 2 for the reception of a conductor 3, an upper clamping or shoe member 4 and a supporting or suspension element 5.

- 6 The lower clamping or channel member 2 comprises oppositely disposed aligned flared end portions 7 and an intermediate substantially half-tubular body portion 8 that constitutes a continuation of the end portions 10 7 and is displaced laterally upwardly from the axes of the portions 7. The member 2 also comprises a depending loop portion 9, upwardly projecting side lugs 10 and a central seat portion 12.
- 15 The upper clamping shoe or member 4 is provided with flared end portions 14, opposite the end portions 7 of the lower member 2, a half-tubular body portion 15, substantially conforming to the laterally offset portion 8 of the lower member 2, side portions 17 of inverted substantially cup-shape telescopically fitted over the lugs 10 of the lower member 2, and lugs or projections 18 for supporting and securing the ends of a leaf spring 20.

20 The supporting or suspension element 5 is substantially in the form of a yoke having an upper portion 22 of any suitable form, such as a socket, for attachment to the lower 30 end of a suspension insulator string (not shown), and depending side leg portions 23 having apertured lower end portions 24 for the reception of a block or seat member 25 and a pin 26 that extends through the portions 24 and 25 and is held in position, as by 35 a cotter pin 27.

40 The seat member 25 is provided with an arcuate upper seat portion 29 for the reception of a ball-bearing member 30 which may similarly cooperate with an arcuate seat surface on the seat portion 12 or, as shown, the seat portion 12 may be provided with an aperture for the reception of a body 32 for rigidly securing the ball member 30 to the 45 seat portion 12. The body 32 may be in the form of a screw cooperating between the ball 30 and the seat portion 12 or, as shown, may constitute a body of material welded in position to the ball member 30 and to the seat portion 12, such constructions being merely suggestive of any suitable means for positioning the bell.

50 The spring member 20 supports a cam member 34 having an upper surface 35 that, in the clamping condition of the parts, is spherically curved about the center of the ball 30 and extends along the conductor from each side of its center, in the normal vertical condition of the suspension element 5, for about thirty degrees and for a certain distance lateral to, or about, the conductor axis.

55 A second ball member 38 is loosely secured in the upper central portion of the yoke 5, as by overhanging lips 39, to cooperate with 60 the surface 35 to compress the spring 20 and

thereby transmit clamping forces between the clamping members 2 and 4 through the yoke 5.

The parts are shown in the normal operating positions which they assume when the 70 line conductor 3 is stationary, under which condition, the ball 38 is at the center of the surface 35 on the cam member 34.

In response to limited torsional or twisting movement of the conductor 3, all of the 75 parts associated with the clamping members 2 and 4, as distinguished from the yoke 5 and its associated parts, move laterally a limited distance in either direction, while the ball 38 remains on the surface 35 to sustain the 80 clamping forces of the spring 20. Also, under normal longitudinal oscillations of the conductor, the ball 30 similarly remains on the surface 35 and rides back and forth thereon, without diminishing the clamping forces. 85

90 However, when, in response to breakage of the conductor or other cause, the yoke member 5 moves angularly relative to the clamping members 2 and 4 a sufficient distance to the right or to the left, as viewed in Fig. 1, 95 the ball 38 rides off the surface 35 to permit the release of the spring 20 and, consequently, the release of the clamping members 2 and 4 and of the conductor 3.

100 The loop portion 9, at the under side of the under clamping member 2, permits the above-mentioned universal movement of the clamping members on the block member 25 and guards against separation of the clamping members from the suspension element or 105 yoke structure.

110 Referring to the modification of my invention shown in Figs. 3 and 4, in which corresponding parts are designated by corresponding reference characters, the structure 105 and operation are similar, except that the spring 20 is omitted and the clamping forces are transmitted directly between the clamping members 2 and 4 through a cam member 40 that is supported by upwardly-projecting side portions 41 of the clamping member 2.

115 Also, instead of the lugs 10 and the cup portions 17 on the members 2 and 4, respectively, which are provided to prevent longitudinal displacement of the members 2 and 4, accidental disassembly of the clamping members is prevented by a loop portion 42 on the shoe 4, which interlinks a roller or cam portion 43 that is held in position, at the lower end of the cam member 40, by a 120 pin 44.

125 A cam bearing surface 45, on the shoe member 4, is provided with a slightly depressed accentuating portion 46 for the normal central clamping position of the roller 43 which does not normally ride on the surface 45, as does the ball member 38 on the surface 35 of the above-described structure, but remains stationary under normal line conditions and is only moved out of this position when the 130

line breaks or the yoke 5 is otherwise caused to move angularly a sufficient distance about the center of the ball 30.

The above-mentioned operation is permitted by diverging lugs 48 on the cam member 40 which are disposed in spaced relation at opposite sides of a depending central lug 49 on the portion 22 and are engaged by the lug 49 only under abnormal conditions, as 10 above set forth.

In this form also, the body 32 for securing the ball 30 in position cooperates with the lower clamping member 2 instead of the upper clamping member 4.

15 Also, instead of the removable block 25 at the lower end of the yoke 5, as in the structure shown in Figs. 1 and 2, the lower end of the yoke 5, in this form of my invention, is integral with the side legs 23, and the upper 20 portion 22 is removably secured in position, as by a main pin 50 and a cotter pin 51.

25 The portion 22 is fitted between inwardly extending lugs 52, at the upper ends of the side legs 23 of the yoke 5, whereby it may be held rigidly in position, by the single bolt 50.

Under normal line-operating conditions, the clamping members 2 and 4 and associated parts may be moved universally about the center of the ball 30 through limited relative 30 distances, the spaced relation of the lugs 48 to the lug 49 permitting such movement.

However, when the yoke member 5 moves a sufficient distance, about the center of the ball 30, to the right or to the left, as viewed 35 in Fig. 3, the lug 49 engages one of the lugs 48 to move the roller 43 off the surface 45 into one of depressions 54 at the side thereof to release the clamping members and the conductor.

40 In the form of my invention shown in Figs. 3 and 4, the clamping effect depends upon the inherent yieldability of the conductor 23 and play between the other parts but may be augmented or adjusted by the addition of further yieldable means, the omission of play between the parts or other suitable expedient.

In both forms of my invention, above set forth, having the center of universal movement substantially on an axis that would be 45 the longitudinal axis of the conductor in a clamp having a straight conductor seat, prevents the transmission of lateral-component vibrating stresses in any direction between the clamping members and the yoke. Thus, 55 the effects are avoided that usually obtain in ordinary clamps to loosen insulator pins, tower bolts and other parts, and it is contemplated that, in addition to its advantages per se or within the clamp itself, the use of the 60 invention may result in material economy in tower construction, as well as render the installation more permanent and effective in operation.

While I have shown and described particu- 65 lar forms of my invention, changes may be

effected therein without departing from the spirit and scope thereof, as set forth in the appended claims.

I claim as my invention:

1. In a line-conductor support, a suspension element having a portion of substantially loop-shape, an elongated conductor-receiving element extending through, and supported by, the loop portion in relatively movable relation thereto, adjacent to the bottom thereof, said conductor-receiving element being arched at its mid portion, and bearing means between said elements beneath, and adjacent to, the crown of said arched portion. 70

2. In a line-conductor support, a suspension element having a portion of substantially loop-shape, an elongated conductor-receiving element extending through, and supported by, the loop portion in relatively 75 movable relation thereto, adjacent to the bottom thereof, said conductor-receiving element being arched at its mid portion and having portions projecting from ends of the arch at an angle thereto, and bearing means 80 between said elements within a space bounded by the arch and a straight line between 85 said ends. 90

3. In a line-conductor support, a suspension element having a portion of substantially 95 loop-shape, an elongated conductor-receiving element extending through, and supported by, the loop portion in relatively movable relation thereto, adjacent to the bottom thereof, said conductor-receiving element being arched at its mid portion, and substantially ball-and-socket bearing means 100 between said elements beneath, and adjacent to, the crown of said arched portions. 100

4. In a line-conductor support, a suspension element having a portion of substantially 105 loop-shape, an elongated conductor-receiving element through, and supported by, the loop portion in relatively movable relation thereto, adjacent to the bottom thereof, said conductor-receiving element being arched at its mid portion, bearing means between said elements beneath the crown of said arched portion, and an inverted substantially arched portion 110 on said conductor-receiving element and extending between points at opposite sides of 115 said bearing means around the under side of the latter. 115

5. In a line-conductor support, a suspension element having a portion of substantially 120 loop-shape, an elongated conductor-receiving element extending through, and supported by, the loop portion in relatively movable relation thereto, adjacent to the bottom thereof, said conductor-receiving element being arched 125 at its mid portion, bearing means between said elements beneath, and adjacent to, the crown of said arched portion, and means co-operating between said suspension loop and conductor-receiving channel elements for nor- 130

mally holding the conductor in predetermined position and responsive to a predetermined movement of the conductor to release the conductor.

- 5 6. In a line-conductor support, a suspension element having an upper mounting portion and a lower portion of substantially loop-shape, and an elongated conductor-receiving element extending through, and supported by,
10 the loop element in relatively movable relation thereto, and an inverted substantially arched portion on said conductor-receiving element and extending between points at opposite sides of said suspension loop portion
15 around the under side of the latter.
7. In a line-conductor support, an elongated conductor-receiving member, a member for supporting the same at an intermediate portion thereof in relatively movable relation
20 thereto about a given point, and means on, and cooperating with, said conductor-receiving member to constitute substantially a loop in eccentric relation to said point about said supporting member and having the greater part of its perimeter spaced substantially from said supporting member.
8. In a line-conductor support, a suspension element of substantially loop-shape, an elongated conductor-receiving channel element
30 extending through, and supported by, the loop element in relatively movable relation thereto, adjacent to the bottom thereof, in spaced relation to the upright sides of the loop element, said conductor-receiving element being arched at its mid portion and having portions projecting from the ends of the arch at an angle thereto, substantially ball-and-socket bearing means between said elements within a space bounded by the arch and
35 a straight line between said ends, and means cooperating between said suspension-loop and conductor-receiving channel elements for normally holding the conductor in predetermined position and responsive to a predetermined movement of the conductor to release the conductor.

In testimony whereof, I have hereunto subscribed my name this 10th day of November, 1927.
